UNITED STATES PATENT OFFICE.

WILLIAM D. FERRIS, OF STERLING, ILLINOIS.

DESIGN FOR A HINGE-LEAF.

42,168.

Specification for Design.

Patented Feb. 13, 1912.

Application filed September 28, 1908. Serial No. 455,220. Term of patent 7 years.

To all whom it may concern:

Be it known that I, WILLIAM D. FERRIS, a citizen of the United States, residing at Sterling, in the county of Whiteside and State of Illinois, have invented a new, original, and ornamental Design for a Hinge-Leaf, of which the following is a specification, reference being had to the accompanying drawing, forming part thereof.

The figure is a plan view of a hinge leaf, showing my new design.

I claim:

The ornamental design for a hinge leaf, as shown.

WILLIAM D. FERRIS.

Witnesses:

JOHN B. HOWAT,

WILLIAM A. STOECKLE.
